D. W. McNEIL,
DRINKING FOUNTAIN,
APPLICATION FILED MAY 18, 1912.

1,165,428.

Patented Dec. 28, 1915.

UNITED STATES PATENT OFFICE.

DANIEL W. MCNEIL, OF CINCINNATI, OHIO, ASSIGNOR TO THE JOHN DOUGLAS COMPANY, OF CINCINNATI, OHIO, A CORPORATION OF OHIO.

DRINKING-FOUNTAIN.

1,165,428.

Specification of Letters Patent. Patented Dec. 28, 1915.

Application filed May 18, 1912. Serial No. 698,098.

To all whom it may concern:

Be it known that I, DANIEL W. MCNEIL, a citizen of the United States of America, and resident of Cincinnati, county of Hamilton, and State of Ohio, have invented certain new and useful Improvements in Drinking-Fountains, of which the following is a specification.

An object of my invention is to produce a new and improved drinking fountain in which means are employed for overcoming difficulties encountered in fountains now in use. This and other objects I attain in a fountain embodying the features herein described, and illustrated in the drawings accompanying and forming a part of this application.

In the drawings Figure 1 is a fragmental, sectional elevation of a fountain embodying my invention. Fig. 2 is a perspective view of a drip pan or catch basin forming a detail of my invention, a section being removed for the sake of illustration.

One of the difficulties encountered with drinking fountains is that the standards or pedestals of the fountains vary in size and shape, even though they are carefully formed, and therefore render it difficult to assemble the parts in the operation of erecting the fountain. This difficulty is encountered more often in fountains employing porcelain or earthenware pedestals since the firing operation causes the pedestals to vary in size and shape even when they are carefully molded.

An object of this invention, is, therefore, to provide an improved construction in which means are employed for overcoming the difficulties resulting from the shrinkage or distortion of the pedestals during the firing process.

Referring to the drawings, the pedestal 3, illustrated, is formed of porcelain or earthenware and is open at the lower end so as to provide an entrance for the water supply pipe 4 and the drainage pipe 5. The lower end of the pedestal is also provided with an annular flange 6 which is employed in securing it in place on the floor or on its foundation, the flange 6 being provided with apertures through which a holding screw or bolt may be inserted.

The upper end of the pedestal, illustrated, is provided with an integrally formed catch basis 7 which is provided with a centrally

located aperture 8 through which the drinking water is delivered to the drinking device or bubbler. An annular shoulder is formed integrally with the basin 7 and is located around the aperture 8, and supports the cup 9 of the bubbler, which, as illustrated, is provided with a ported diaphragm 10, upon which the nozzle 11 of the bubbler is adapted to be mounted. I preferably provide a soft washer 12 between the nozzle and the diaphragm 10 for the purpose of providing a water tight joint. Inwardly extending apertures 13 are formed in the walls of the cup 9 below the diaphragm 10 and are so located that they are capable of draining the water from the catch basin into a drip pan 14 which is located immediately below the aperture 8 and within the pedestal.

The drip pan is preferably made of metal and is provided with a centrally located tapped aperture 14' into which a short section of pipe 15 is screwed. The upper end of the pipe 15 is also screw threaded, and is employed both in delivering water to the nozzle 11 and also in securing the nozzle and the cup 9 in place. The lower end of the water passage through the nozzle is screw threaded and the nozzle is adapted to be screwed onto the pipe 15 so that it, in effect, forms a cap nut for the pipe and thereby secures the cup 9 against the shoulder surrounding the aperture 8. The supply pipe 4, which is disposed within the pedestal 3, is provided with a stop cock 16 which, as illustrated, is secured to the upper end of the pipe 4, and is located immediately adjacent to the pan 14, so that the pipe section 15 is screwed into it as well as into the aperture 14'. This locks the cock 16 and the pan together. The pan 14 is also provided with a drainage aperture 16' which is adapted to receive the threaded end of the drain pipe 5 which is also located within the pedestal. The lower end of the pipe 5 communicates with a trap 17 which is located within the pedestal and communicates with a drain pipe 18.

Both the supply pipe 4 and the drain pipe 5 are secured to the drip pan 14, but the only means of connection between the drip pan and the pedestal is the pipe 15 which establishes communication between the supply pipe 4 and the nozzle 11. This construction permits of considerable variation.

in the relative positions of the nozzle and the pan since the pipe section 15 can be screwed varying amounts into both the nozzle 11 and the stop cock 16 without detrimentally affecting the operation of the fountain. In addition to this the pan 14 is so formed and located within the pedestal that it can occupy various positions relatively to the catch basin 7 and the drainage apertures 18, without detrimentally affecting the operation of the fountain. This arrangement of parts therefore permits the pedestals to vary considerably in shape and size without rendering it difficult to assemble the parts. The construction also enables the factory to make a number of connections, which is advantageous, since the connections can then be soldered and be rendered permanent.

The operation of assembling the parts of the fountain is somewhat as follows: The pipe section 15, the pan 14, the stop cock 16 and the section 4 of the supply pipe are all permanently secured together in the factory and are shipped as one piece. The section 5 of drain pipe 5 is also cut to the proper length and is screw threaded at its upper end. The trap 17, which may be of any suitable type is secured in place on the drain pipe 18 after which the lower end of the pipe section 4 is screwed into the socket or sleeve 19, provided on the upwardly projecting end of the water supply pipe and located near the floor or the surface of the foundation for the pedestal 3. The plain end of the drain pipe 5 is then inserted into the trap 17 and the upper end is tightly screwed into the aperture 16 of the pan 4. After the connection between the pipe 5 and the trap is tightened up the pedestal is placed in position over the pipes 4 and 5 so that the pipe 15 projects upwardly through the centrally located aperture provided in the catch basin 7. The nozzle 11, and the soft washer 12 are then located in place on the diaphragm 10 of the cup 9, and the cup and nozzle are turned as one piece while the nozzle 11 is being screwed onto the pipe section 15. The nozzle and cup are screwed down on the pipe until the lower end of the cup 9 abuts against the shoulder surrounding the aperture 8. The floor screws can then be inserted through the apertures provided in the flange 6. An aperture 20 is provided in the pedestal for the purpose of giving access to the stop cock 16. In placing the pedestal over the pipes 4 and 5 it should be turned so that the aperture 20 is located opposite to the stop cock.

By providing the separately formed drain

pan 14 the operation of assembling the parts 60 of the fountain is greatly simplified, and the fountain operates effectively even though the pedestal 3 varies somewhat from its proper size.

In accordance with the patent statutes I 65 have illustrated and described what I now consider to be the preferred embodiment of my invention, but I desire it to be understood that various changes, substitutions and modifications may be made in the apparatus illustrated without departing from the spirit and scope of my invention as set forth by the appended claims.

What I claim is:

1. In combination in a drinking fountain, 75 a pedestal, a catch basin located thereon and having a drainage aperture formed therein, a separately formed drip pan located below the drainage aperture and within the pedestal, water supply piping extending through and adjustably supporting the drip pan and projecting upwardly through the drainage aperture, a waste pipe secured to the drip pan, a bubbler located in the catch basin above the drainage aperture and comprising a cup having a ported diaphragm and a nozzle located within the cup on the diaphragm and secured to the supply piping.

2. In a drinking fountain, a pedestal, a 90 catch basin, having a drainage aperture, a water supply pipe located within the pedestal and projecting upwardly through the aperture, a bubbler mounted on the catch basin over the aperture, and comprising a 95 separately formed cup, having drainage apertures formed therein and communicating with the aperture in the basin, a nozzle mounted on the cup and secured to the supply pipe, a separately formed drip pan located in the pedestal below the drainage aperture, and a drain pipe secured to said pan.

3. In a drinking fountain, a pedestal, a catch basin having a drainage aperture 105 formed therein, a separately formed drip pan located within the pedestal adjacent to the catch basin and below the drainage aperture, a drain pipe secured to the drip pan, a 110 nozzle located within the catch basin, a water supply pipe passing through the drainage aperture and drip pan and adapted to secure the nozzle and drip pan in place.

DANIEL W. McNEIL.
